(57) **CLAIM**

The ornamental design for an exercise device, as shown and described.

DESCRIPTION

FIG. 1 is a perspective view of our new design;
 FIG. 2 is top view thereof;
 FIG. 3 is the bottom view thereof;
 FIG. 4 is a right side view of the design of FIG. 1, the left side view being a mirror image thereof;
 FIG. 5 is the rear view thereof; and,
 FIG. 6 is the front view of our new design.
 The features shown in dashed lines in FIGS. 1, 3, 4, 5, and 6 are for illustrative purposes only and form no part of the design.
